CLAIM

The ornamental design for a cap and retainer assembly, as shown and described.

DESCRIPTION

FIG. 1 is a perspective view showing the design of a cap and retainer assembly;

FIG. 2 is a front view of the cap and retainer assembly design of FIG. 1 as seen from 2—2 of FIG. 1;

FIG. 3 is a rear view of the design of FIG. 1 as seen from 3—3 of FIG. 1;

FIG. 4 is a rear view of the design of FIG. 1 as seen from 4—4 of FIG. 1;

FIG. 5 is a right side view of the design of FIG. 1, the left side view being the same; and,

FIG. 6 is a perspective view of the design of FIG. 1 with the cap shown in its dismounted position.

The broken line showing of a marking pen is for illustrative purposes only and forms no part of the claimed design.
